Philip Van Cleave Fish

UNITED STATES PATENT OFFICE.

ALBERT H. MORTON, OF LOWELL, MASSACHUSETTS.

SPINNING-FRAME.

1,165,620.

Specification of Letters Patent. Patented Dec. 28, 1915.

Original application filed March 15, 1915, Serial No. 14,357. Divided and this application filed October 15, 1915. Serial No. 56,121.

To all whom it may concern:

Be it known that I, ALBERT H. MORTON, a citizen of the United States, residing at Lowell, in the county of Middlesex and 5 State of Massachusetts, have invented certain new and useful Improvements in Spinning-Frames; and I do hereby declare the following to be a full, clear, and exact description of the invention, such as will enable others skilled in the art to which it 10 appertains to make and use the same.

The present invention relates to improvements in spinning frames.

The object of the invention is to improve 15 the construction of the thread guide, thread board, doffing rail and associated parts, and to this end, the invention consists in the improvements hereinafter described and particularly pointed out in the claims.

20 In the accompanying drawings illustrating the invention Figure 1 is a plan of the doffing rail of the spinning frame showing the thread board attached thereto and showing their relative position to the roll bosses 25 of the drawing rolls; Fig. 2 is a plan of one of the thread boards shown in Fig. 1; and Fig. 3 is a longitudinal sectional elevation of the same on the line 3—3 Fig. 2.

The thread guide, which is of the kind 30 known as a "vibrating" thread guide, not because it vibrates but because the thread vibrates in it, has a D-shaped guide passage, the long straight side of which affords ample surface for wear, thereby preventing 35 grooving of the guide.

The thread guide 20 is supported on the thread board 21 in such wise as to be adjustable for the purpose of bringing the straight side of the D-shaped thread passage 40 into position normal to the direction of the line of the thread running from the drawing rolls 13 to the guides, and this is secured by providing the thread guide with a shank 22 curved so that when it is adjusted it turns the guide about a center which is the center of the spindle to which the guide delivers its thread. Thus, referring to Fig. 1, it will be observed that the spindle 23 is the center of curvature of 45 the shank 22 of the thread guide 20, and that the thread guide 20, when the clamp is loosened, may be turned about such spindle center. The under side of the front end 50 of the thread board 21 is grooved to receive the curved shank 22 of the thread guide, 55 and a clamp 24, having a correspondingly shaped groove is provided for securing the thread guide in adjusted position. The clamp 24 is a third class lever, having its fulcrum at 25, being secured in place by 60 means of the screw 26. The curvature of the shank of the thread guide prevents any tipping of the thread guide with respect to the thread board.

The thread board support 30 is secured 65 to the under side of the doffing rail 31 at points corresponding to the positions of the spindles. A bolt 32 is employed for this purpose. The thread board support 30 is slotted at 33 to receive the bolt 32 and to 70 permit adjustment longitudinally so as to bring the thread guide in proper position with respect to the spindle.

The features of advantage of this construction will be apparent to those skilled 75 in the art. In the first place, the locations of the thread boards correspond to the spindle locations, and are, therefore, equally spaced throughout the length of the frame, conducing to convenience of manufacture. 80 In the second place, accidental variations between the positions of the thread boards and the spindles, owing to any inaccuracy of manufacture, may be compensated for by the two adjustments provided for the thread 85 guide, the one, the longitudinal adjustment provided by slotting the thread board support, and the other, the thread guide adjustment provided by the means for permitting the thread guide to be turned so as 90 to present its straight side normal to the direction of the thread. Again, the worn thread eyes may be replaced with the utmost ease, and when replaced, adjusted with the utmost facility, to correct position. 95 Furthermore, in case of any incorrectness of position of the center of the thread guide with relation to the spindle center, the thread guide, thread board, and thread board support, may all be swung together 100 laterally, so as to correct the position of the thread guide with relation to the spindle. It will thus be seen that this construction lends itself to other spacing on the doffing rail than that shown.

Having thus described my invention, what is claimed is:—

1. A spinning frame having, in combina-

tion, drawing rolls, spindles, a doffing rail, a thread board, a thread guide having an arcuate shank mounted on the thread board and a clamp for engaging the arcuate shank 5 for permitting adjustment of the thread guide.

2. A spinning frame having, in combination, drawing rolls, spindles, a doffing rail, a thread board supported on the doffing 10 rail, a thread guide having a straight thread-engaging surface supported by the thread board, and an arcuate shank supported by the thread board and a clamp for engaging the shank of the thread 15 guide to permit the straight thread-engaging surface thereof to be engaged perpen-

dicularly to the line of the thread from the rolls to the spindles.

3. A spinning frame having, in combination, drawing rolls, spindles, a doffing rail, a thread board supported on the doffing rail, 20 a thread guide having a straight thread-engaging surface supported by the thread board, and means for adjusting the thread guide on the thread board whereby the straight thread-engaging surface of the 25 thread guide is positioned perpendicular to the line of the thread leading from the rolls to the spindle.

ALBERT H. MORTON.
